UNITED STATES PATENT OFFICE.

ZENAS CRANE, JR., OF DALTON, MASSACHUSETTS.

DESIGN FOR WRITING-PAPER.

SPECIFICATION forming part of Design No. 16,080, dated May 12, 1885.

Application filed April 6, 1885. Term of patent 7 years.

To all whom it may concern:

Be it known that I, ZENAS CRANE, Jr., a resident of Dalton, in the county of Berkshire and State of Massachusetts, have invented and produced, by my own industry, genius, efforts, and expense, a new and original Design for Writing-Paper, of which the following is a full description, in connection with the accompanying photograph, which represents a face view of my new design for writing-paper.

This invention relates to a new ornamentation of the face of writing-paper.

In the accompanying photograph are represented the various parts which enter into my new design.

The flat face of the paper is, by light lines,

which are shown as water-marks, which in the photograph are represented by light lines A, divided into square fields B B, the corner of each square where four lines converge showing an enlargement, a, or spot, which spots are of irregular outline.

I claim—

The design for flat writing-paper, the same consisting of the lines A A, crossing each other, and of the irregularly-shaped spots a, which are located at the points of crossing of said lines, substantially as shown.

ZENAS CRANE, JR.
